CARRYING SCRAPER

Marion A. Clark, Tulare, Calif.

Application June 6, 1945, Serial No. 597,798

1 Claim. (Cl. 37—9)

1

This invention relates to an improved earth working implement, and particularly an earth digging, carrying, and dumping scraper.

An object of this invention is to embody, in a carry-type scraper, novel means for mechanically elevating earth from an independently mounted scraping blade upwardly for discharge some distance above the blade into a normally upwardly opening earth receiving bowl; said bowl being rotatably mounted so that it may be inverted to discharge a load, and there being power means arranged to control the position of said bowl.

Another object of the invention is to provide a scraper, as in the preceding paragraph, in which the bowl is cylindrical; said earth elevating means comprising a reel surrounding the bowl in rotatable relation, the reel including a plurality of longitudinally extending, circumferentially spaced earth elevating vanes, and there being an arcuate earth retaining hood extending circumferentially about the reel from the blade to substantially the point of discharge of earth into the bowl; the reel running between said bowl and hood whereby earth carried by the reel is confined against escape until discharged into said bowl.

A further object of the invention is to mount the digging blade on the lower edge of the hood, and to power actuate the hood about the axis of the bowl to raise or lower the blade; there being supporting wheels associated with the hood in a manner such that when the blade is in digging position the wheels are clear of the ground, but when the blade is raised to a certain extent, the wheels engage the ground and support the scraper bowl and reel clear for transport.

A further object of the invention is to produce a simple and inexpensive device, and yet one which will be exceedingly effective for the purpose for which it is designed.

These objects are accomplished by means of such structure and relative arrangement of parts as will fully appear by a perusal of the following specification and claim.

In the drawings similar characters of reference indicate corresponding parts in the several views:

Figure 1 is a sectional elevation of the scraper in loading position.

Figure 2 is a side elevation, partly in section, of the scraper in discharging position.

Figure 3 is a plan view of the scraper, with the power cylinders removed.

Referring now more particularly to the characters of reference on the drawings, the scraper comprises a main frame 1 which includes a for-

2

wardly projecting draft assembly 2 adapted for connection with a tractor, and which draft assembly may be supported at its forward end, if desired, by a wheel truck 3. The frame 1 also includes a pair of rigid, rearwardly extending side beams 4 disposed in relatively widely spaced parallel relation.

Adjacent their rear ends the side beams 4 are connected by a heavy-duty cross shaft 5 journaled in connection with and projecting a short distance outwardly of said beams.

Between the side beams 4 the shaft 5 supports a cylindrical earth receiving and carrying bowl 6, said bowl having a full width but circumferentially limited opening 7 therein, and said opening is normally disposed at the top of the bowl, as shown in Fig. 1.

The cylindrical bowl 6 is surrounded in relatively close but rotatable relation by an earth elevating reel, indicated generally at 8, and which reel comprises circular end plates 9 journaled on the cross shaft 5 between the ends of the bowl 6 and the side beams 4. The circular end plates 9 are connected together outwardly of the bowl 6 by longitudinally extending, circumferentially spaced earth elevating vanes 10; said vanes being of substantial width and extending radially of the bowl and the reel.

An arcuate, earth retaining hood 11 of somewhat less than 180° extent extends circumferentially about and cooperates with the reel at the back thereof; said hood including forwardly projecting end plates 12 which include laterally outwardly offset legs 13 journaled in connection with the cross shaft 5 outwardly of the side beams 4. The legs 13 are of a length such that they project some distance beyond the cross shaft 5, and in a direction centrally opposite the hood 11. At their outer ends the legs 13 are fitted with outwardly extending spindles 14 which carry ground engaging wheels 15.

At its lower edge the hood 11 is fitted with a transverse, earth scraping or digging blade 16; the arrangement being such that when the blade 16 is in earth engagement below the cylindrical bowl 6, the wheels 15 are clear of the ground, as shown in Fig. 1.

The rotary position of the hood 11 is controlled by double-acting power cylinders 17 which connect between upstanding posts 18 on the side beams 4 ahead of the bowl and the adjacent forward edge portions of the end plates 12 of the hood 11 at points adjacent the periphery of the latter. The power cylinders 17 are controlled from the tractor by a conventional valved fluid

pressure system. When the cylinders 17 are extended the hood 11 occupies a rotative position with the blades 16 in ground engaging or working position, as shown in Fig. 1, and at which time the wheels 15 are clear of the ground, with the reel 8 riding the ground ahead of said blade 16. However, when the cylinders 17 are contracted, as shown in Fig. 2, the hood is swung to a raised position so that the blade 16 is clear of the ground; the wheels then riding the ground with the bowl 6 and reel 8 clear thereof. This is the transport position of the scraper.

When the scraper is in working position, as in Fig. 1, earth is dug or scraped up by the blade 16 with advance of the implement. As the implement advances, the reel—on account of its ground engagement—rotates in a clockwise direction and the vanes 10 pick up the earth dug by the blade 16 and sweep such loose earth upwardly between the hood 11 and corresponding portion of the bowl 6 until such earth reaches the normally upwardly facing opening 7. As the vanes reach such opening the loose earth falls through said opening into the bowl 6.

When the bowl 6 is filled, as above described, the hood 11 is actuated to raise the blade 16 and lower the wheels 15 into ground engagement for transport of the load.

After the load has been transported to the point of discharge, the bowl 6 is rotated so as to cause the opening 7 to move toward the bottom of the bowl, and at which time the load spills through said opening. The bowl 6 is so rotated between its loading and dumping positions by means of the following power mechanism:

Power cylinders 19 are pivotally mounted, as at 20, in connection with the posts 18, and the piston rods 21 of said cylinders are formed with rearwardly projecting racks 22, which cooperate in meshing engagement with pinions 23 fixed on the cross shaft 5 outwardly of the legs 13. The racks 22 are maintained in mesh with the pinions 3 by suitable roller hold-down units, indicated generally at 24. It will be seen that by actuation of the power cylinders 19 the bowl 6, which is fixed on cross shaft 5, may be positively rotated, and to controlled extent, between loading and dumping positions; the bowl being in loading position when the racks are advanced, and in dumping position when the racks are contracted.

With the improved scraper, as above described, the bowl 6 may be fully loaded with relative ease;

the earth elevating reel assembly assuring of positive loading of said bowl. In addition, the reel, as it rides the ground during a loading operation, tends to loosen the earth directly ahead of the blade 16, for the reason that the vanes dig into the earth in the manner shown in Fig. 1. This facilitates the digging operation and makes it easier for the blade 16 to progress through the earth.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful and upon which Letters Patent is desired:

A scraper comprising a draft frame, a rotary bowl mounted on the frame for rotation about a transverse axis, said bowl having a circumferential opening therein, means to control rotation of the bowl between a loading position with the opening on top and a dumping position with the opening on the bottom, a transverse scraper blade mounted for earth engagement below and spaced from the bowl, an arcuate hood extending upwardly and rearwardly from the blade in spaced symmetrical relation to the bowl to a point adjacent the top of the latter, and an earth elevating reel rotatably surrounding the bowl and running between the latter and said hood whereby to elevate earth from the blade and to load said earth into the bowl from the top; the hood and blade being secured in unitary relation and the hood including end members projecting radially across the ends of the bowl, means pivoting said end members intermediate their ends axially of the bowl, supporting wheels mounted on said members at the end opposite the hood, the wheels being clear of the earth when the blade engages therewith, and means to rotatably adjust the hood between one position with the blade in earth engagement and the wheels clear thereof, and another position with the blade clear of the earth and the wheels in engagement therewith.

MARION A. CLARK.
